CLAUDE M. DIBBLE, OF JOLIET, ILLINOIS, ASSIGNOR TO MOORE BROTHERS COMPANY,
OF JOLIET, ILLINOIS, A CORPORATION OF ILLINOIS

EXPLOSION RELIEF

Application filed February 8, 1928. Serial No. 252,900.

This invention relates to fluid fuel heaters, and while the invention will be hereinafter described as embodied in the type known as parlor gas heaters, it will be readily understood that it has valuable application in furnaces, cooking and other stoves, etc. using oil and other fluid fuels.

The use of parlor heaters encased in a cabinet of attractive design or harmonizing with articles of furniture has become well known and rather widespread. Both coal and gas have been used as fuel but gas stoves of this nature have been somewhat unpopular, due to the fact that should the flames go out, either from the main burners or from the pilot lights, without turning off the gas, when the stove was subsequently lighted, an explosion of more or less violence took place which might have disastrous results. This was due to the fact that the explosion was practically confined to the combustion chambers. As far as I am aware, no means have heretofore been devised to effectively lessen the force of the explosion within the combustion chambers and so dissipate its effect.

It is the object of this invention to provide a means whereby the force of an explosion within the combustion chambers may be lessened with the attendant lowering of possible damages to the stove and to the person operating it.

It is a further object of this invention to provide a means to prevent the propagation of the flames in an explosion which escape through my previously mentioned means from being spread in undesirable directions, such as through the bottom of the stove.

One of the novel features of my invention is the provision for venting each combustion chamber, which will open under the force of an explosion to reduce the force thereof within the chamber.

Another novel feature of my invention is in the location of explosion vents positioned substantially opposite each other on opposite sides of the respective combustion chambers at substantially the same elevation as the burners within the combustion chamber.

Another novel feature is the means used and method of locating the means to prevent

the undesirable propagation of the flames of an explosion.

Numerous other objects and advantages of the invention will be apparent as it is better understood from the following description, which, taken in connection with the accompanying drawings, discloses a preferred embodiment thereof.

Referring to the drawings:

Figure 1 is an end view of a stove or heater of the type to which my invention is applicable, the dotted lines showing the combustion chamber, the explosion vents and the means for preventing the propagation of the flame in undesirable directions, and

Fig. 2 is a perspective view of the combustion chamber of such a heater showing the relationship of the vents to the burners and pilot lights and to the baffles which I use to prevent the spreading of the flames.

More particularly, a combustion chamber 11, having two members 12 and 13, is placed within a cabinet 14 supported upon legs 15 and having a grilled closure 16 at the top. A flue 22 is provided leading from the combustion chamber through the air space in the cabinet to a chimney or similar outlet. In each of the members of the combustion chamber is the usual burner 17 and pilot light 19. Each burner is equipped at its intake end with the usual air-mixing valve 18. Hand holes 21 are provided as usual for lighting the burners. On each side of each member of the combustion chamber I place vents 31 positioned substantially opposite each other on each combustion chamber. It is these vents which permit the lessening of the explosion force within the combustion chamber and it is to be noted that they are placed at approximately the same height as the burners.

The vents themselves are comprised of a frame 25 mounted upon the sides of the combustion chamber members and doors 23 which are attached to the frame by suitable hinges 24. It is to be noted that these doors will normally remain closed due to the effect of their own weight. It is also pointed out that the frame 25 has a projecting portion which extends in an upward manner so that a flame coming from the combustion chamber would

be directed upwards. This projecting portion also acts as a rest for the door in its closed position.

A baffle is provided beneath each vent and these baffles are indicated by reference characters 26, 27, 28 and 29 on Fig. 1 of the drawings. It will be noted that the outer baffles 26 and 27 are of construction and arrangement similar to the inner baffles 28 and 29. These last mentioned baffles are, however, larger than the side baffles and are placed between the adjacent members of the combustion chamber and are located one beneath the other so that while there is a passage between them they act together to prevent any flame from being forced downward. The cabinet is generally opened at its bottom and air circulates up around the combustion chambers and is discharged in heating condition through the top 16 of the stove. The arrangement of the baffles described prevents downward projection of the flame in the event of explosion through the open bottom of the cabinet and consequent ignition of the floor or floor covering beneath.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

1. The combination with a plurality of spaced, vertically and horizontally elongated gaseous fuel burner chambers providing an intermediate air heating chamber, gaseous fuel burners respectively located in said chambers adjacent the bottom and extending substantially the horizontal length thereof, the vertical side walls of said chambers having explosion relief vents directly communicating with the locality of the gaseous fuel burners in said chambers and leading outwardly into the intermediate air heating chamber, doors respectively pivoted at the tops of said vents and movable by gravity to keep them normally closed, and baffles respectively projecting horizontally from the side walls of the fuel burner chambers into the intermediate air heating chamber, said baffles being located below the vents but positioned at different levels to arrest the downward spread of flame discharged through the vents without obstructing the upward flow of air in the heating chamber during normal operation.

2. The combination with a plurality of spaced, vertically and horizontally elongated gaseous fuel burner chambers providing an intermediate air heating chamber, gaseous fuel burners respectively located in said chambers adjacent the bottom and extending

substantially the horizontal length thereof, the vertical side walls of said chambers having explosion relief vents directly communicating with the locality of the gaseous fuel burners in said chambers and leading outwardly into the intermediate air heating chamber, doors respectively pivoted at the tops of said vents and movable by gravity to keep them normally closed, and baffles respectively projecting into the intermediate air heating chamber for arresting the downward spread of flame discharged through the vents.

3. The combination with a plurality of spaced, vertically and horizontally elongated gaseous fuel burner chambers providing an intermediate air heating chamber, gaseous fuel burners respectively located in said chambers adjacent the bottom and extending substantially the horizontal length thereof, the vertical side walls of said chambers having explosion relief vents directly communicating with the locality of the gaseous fuel burners in said chambers and leading outwardly into the intermediate air heating chamber, doors companion to said vents and movable by gravity to keep them normally closed, and baffles respectively projecting horizontally from the side walls of the fuel burner chambers into the intermediate air heating chamber, said baffles being located below the vents but positioned at different levels to arrest the downward spread of flame discharged through the vents without obstructing the upward flow of air in the heating chamber during normal operation.

4. The combination with a plurality of spaced, vertically and horizontally elongated gaseous fuel burner chambers providing an intermediate air heating chamber, gaseous fuel burners respectively located in said chambers adjacent the bottom and extending substantially the horizontal length thereof, the vertical side walls of said chambers having explosion relief vents directly communicating with the locality of the gaseous fuel burners in said chambers and leading outwardly into the intermediate air heating chamber, closure members for said vents yieldable on the development of explosive pressures within the fuel burner chambers, and baffles respectively projecting horizontally from the side walls of the fuel burner chambers into the intermediate air heating chamber, said baffles being located below the vents but positioned at different levels to arrest the downward spread of flame discharged through the vents without obstructing the upward flow of air in the heating chamber during normal operation.

5. The combination with a vertically and horizontally elongated fuel burner chamber, a gaseous fuel burner located in said chamber adjacent the bottom and extending substantially the horizontal length thereof,

the vertical side wall of said chamber having an explosion relief vent directly communicating with the locality of the gaseous fuel burner therein and leading outwardly into the surrounding air space, closure means for said vent yieldable on the development of an explosive pressure within the fuel burner chamber, and a baffle positioned adjacent to said vent for arresting the spread of flame discharged through the vent during the explosion relief.

6. The combination with a plurality of gaseous fuel burner chambers providing an intermediate air heating chamber, gaseous fuel burners respectively located in said chambers, the walls of said chambers having explosion relief vents directly communicating with the locality of the gaseous fuel burners therein and leading outwardly into the intermediate air heating chamber, doors movable normally to keep said vents closed but self-opening during the occurrence of explosive pressures within said fuel burner chambers, and baffles respectively projecting into the intermediate air heating chamber, said baffles being positioned in the locality of the vents to arrest the spread of flame discharged therethrough but spaced to avoid obstructing the normal circulation of air in the heating chamber.

7. A gaseous heater, comprising a combustion chamber having opposite walls provided with an explosion vent, a closure for said vent and movable to open under force of an explosion, and a deflector mounted on said wall adjacent said vent to divert flame issuing through said vent on explosion in said chamber.

8. A gaseous heater, comprising a combustion chamber having opposite walls provided with an explosion vent, a closure for said vent and movable to open under force of an explosion and to automatically close after an explosion to prevent the escape of surrounding heated air through said vent into said chamber, and a deflector arranged laterally on the outside of said wall below said vent to upwardly divert flame issuing through said vent on explosion in said chamber.

50 9. A gaseous heater, comprising an outer casing, inner combustion chambers arranged in spaced relation with said casing, a burner in said chambers, automatically closed explosion vents disposed in opposite walls of said chamber, flame upwardly diverting means arranged in said vents, and laterally disposed flame diverting means arranged on the outside of said combustion chamber and immediately below said vents and arranged to permit free circulation of air through the space surrounding said chamber.

CLAUDE M. DIBBLE.
